CENTRIFUGAL FOAM BREAKER

Laurence Price Sharples, Ardmore, Pa., assignor
to The Sharples Corporation, a corporation of
Delaware

Application August 9, 1944, Serial No. 548,733

8 Claims. (Cl. 233—28)

1

This invention relates to centrifugal foam breakers and more particularly to apparatus of this character so designed as to effectively prevent re-foaming.

The general object of the invention is to provide improved centrifugal apparatus into which the foam is fed, and in which the foam is broken down by centrifugal force into gas and liquid constituents, and from which apparatus the gas and liquid thus formed are continuously and separately discharged.

In order that the invention may be readily understood, reference is had to the accompanying drawing, forming part of this specification, and in which:

The figure is a central longitudinal section through the improved centrifugal apparatus.

Referring to the drawing in detail, 1 designates a centrifugal bowl, preferably cylindrical in shape, and mounted to rotate about a vertical axis. The bowl is closed at the bottom by a head 2 attached as by means of screw threads 3, and is closed at the top by a head 4 secured by screw threads 5.

A plurality of radial wings 6 are rigidly secured to the heads 2 and 4, such wings being preferably cut away to leave open the area at the center, as shown. The purpose of the wings 6 is to impart rotation to the contents of the bowl so that there will be as little slippage as possible between such contents and the side walls of the bowl itself.

Secured to the upper end of the bowl 1 is a rim or wall 9 having at its upper edge an in-turned annular flange 10, thus providing an annular channel between such flange and the upper surface of the head 4.

A stationary skimmer taking the form of an annular skimming nozzle of special construction is arranged in this channel. This skimming nozzle is preferably of the type shown in Patent No. 2,302,168, to Ayres, dated November 17, 1942, and comprises concentric sleeves 12 and 12^a, suitably spaced to form an annular passage between them. These sleeves are provided at their lower ends with overlapping radial flanges 12^b, having between them radially extending abutments (not shown) preferably curved as shown in said patent, and providing wings, forming channels, the outer edges 12^c of said flanges being spaced apart and presenting a smooth annular skimming surface.

The upper ends of the sleeves 12 and 12^a are secured to an annular header 13, from which extends a liquid discharge pipe 14.

Above the upper head 4 extends a central neck 15, and surrounding this neck is a stationary annular trough or channel 16, from which extends a gas discharge pipe 17.

The neck 15 has a central opening 4^a communicating with the interior of the bowl, and from this opening extend a plurality of radial ports

2

18 having their outer ends arranged to discharge into the trough or channel 16. The diameter of the neck 15 is preferably such that these ports 18 have a substantial length, so that they act as a centrifugal pump or impeller.

Above the trough 16, the neck is reduced in diameter and extends upwardly as at 19, and a supporting spindle 20, having a shoulder 20^a, is secured to the neck 19 as by means of a nut 21, which embraces the shoulder 20^a. Thus the bowl 1 is suspended from the spindle 20, which may be driven in the usual or any suitable manner (not shown).

Within bowl 1 is a closed deflecting core 22, shown as formed of a wooden block, and having a tapered or pointed lower end 23, the tip of which is concentric with and spaced from the inlet 1, 8. This core or deflector may be supported at the center of the bowl in any suitable manner, as for example by rods 24 passing through the same and having their ends supported in sockets 25, secured to the side walls of the bowl, the ends of these rods being threaded and provided with nuts 26 by means of which the core may be properly centered and locked in position.

In operation, foam is fed into the bottom of the bowl through the inlet 1, 8 and passes up around the deflecting core through the annular passageway between such core and the side walls of the bowl. In this annular passageway, the foam is subjected to strong centrifugal force, which serves to break down the minute bubbles constituting the foam, thus releasing the gas contained in them, while the liquid forming such bubbles is thrown, by centrifugal force, against the side walls of the bowl.

This layer of liquid gradually works its way up the side walls and passes through openings 11 at the outer edge of the head 4 into the channel formed by the rim 9, where it is picked up by the skimming nozzle 12^c, and discharged through the pipe 14. The gas, on the contrary, tends to move toward the inner portions of the annular passageway, and flows upwardly along the core 22, passing into and through the opening 4^a, the ports 18 and trough 16, from which it is discharged through the pipe 17.

It will be observed that the outer rim 12^c of the stationary skimming nozzle is submerged in liquid which is rotating with the bowl so that air has little if any opportunity to become remixed with the liquid while it is passing from the bowl into the skimming nozzle.

As liquid enters the skimming nozzle, the friction of the rotating liquid against the inner walls of the nozzle results in the liquid in the nozzle losing much of its rotary velocity. Thus, the centrifugal force generated by the liquid within the nozzle is less than the centrifugal force gener-

ated by the liquid adjacent to the nozzle. Hence, there is a differential head tending to force liquid into the nozzle and this will in turn force the liquid up through the pipe 14 even though a pressure of several pounds per square inch is needed to thus elevate the liquid.

It will thus be seen that the liquid rotating within the bowl is discharged into the conduit defined by the members 12, 12^a, 12^b, 12^c and 14, through the lip portions 12^c which are submerged beneath the level of liquid rotating within the space defined by the flange 10 and the upper end 4 of the bowl proper. Since no gas has a chance to enter the conduit, and since the liquid is impelled through that conduit under energy derived from rotation incident to centrifugation, it will be seen that there is no chance for further gas to enter the liquid, and hence no refoaming.

If, as above stated, the ports 18 are of substantial length, they operate in the manner of a centrifugal pump and tend to draw or suck the foam into the inlet 7, 8 and up through the bowl, as described, and to discharge the gas from the pipe 17. However, if desired, the foam may be fed into the bottom of the bowl under slight pressure, generated by an independent pump.

What I claim is:

1. A foam breaker comprising a centrifugal bowl, means for rotating said bowl, means for introducing foam into one end of said bowl, means for confining the flow of foam through said bowl to an annular passageway extending longitudinally of said bowl adjacent its periphery, means for discharging gas from said bowl at its opposite end, and means for skimming off the liquid which accumulates against the side walls of said bowl, said flow-confining means being closed to the entry of foam.

2. A foam breaker comprising a centrifugal bowl mounted to rotate about a vertical axis, means for introducing foam into the bottom of said bowl, means for confining the flow of foam through said bowl to an annular passageway extending upwardly through said bowl adjacent its periphery, means for discharging gas from the center of the upper end of said bowl, wing means in the bowl for imparting rotational movement to the entering mass of foam, and means for continuously discharging the liquid accumulating against the side walls of said bowl, said flow-confining means being closed to the entry of foam.

3. A foam breaker comprising a centrifugal bowl mounted to rotate about a vertical axis, means for introducing foam into the bottom of said bowl, a deflecting core centrally positioned within said bowl for causing such foam to flow upwardly adjacent the side walls of said bowl, means for discharging gas from the upper end of said bowl, and means for continuously discharging the liquid which is thrown outwardly against the side walls of said bowl, said deflecting core being closed to the entry of foam.

4. A foam breaker comprising a cylindrical bowl mounted to rotate about a vertical axis, means for introducing foam into the lower end of said bowl, a deflecting core centrally positioned within said bowl for creating an annular passageway extending longitudinally of said bowl, means for causing the foam to flow upwardly through such annular passageway, means for discharging gas from the center of the upper end of said bowl, and means for discharging the liquid which ac-

cumulates at the outermost zone of said annular passageway, said deflecting core being closed to the entry of foam.

5. A foam breaker comprising a cylindrical bowl mounted to rotate about a vertical axis, a deflecting core centrally positioned within said bowl for creating an annular passageway extending longitudinally of said bowl, centrifugal means for drawing foam in at the bottom of said bowl and causing it to travel upwardly through said annular passageway, means for discharging gas from the top of said bowl, and means for discharging the liquid which is thrown against the side walls of said bowl, said deflecting core being closed to the entry of foam.

6. A foam breaker comprising a centrifugal bowl, means for rotating said bowl, a deflecting core mounted axially within said bowl and forming therewith an annular space, means for introducing foam into one end of said bowl, means for discharging gas from the opposite end of said bowl, and a skimmer means mounted to effect discharge of liquid resulting from the breaking of said foam by passage through said annular space, said deflecting core being closed to the entry of foam.

7. The method of breaking foam comprising introducing it into a rotating centrifugal bowl, the introduction of foam being effected at one end of said bowl; confining the flow of foam through said bowl to an annular passageway extending longitudinally of said bowl adjacent its periphery; discharging from the opposite end of said bowl the gas resulting from the breaking of foam in said annular passageway; and, without permitting the gas to regain access thereto, reducing the rotational velocity of and discharging the liquid resulting from the breaking of foam in said annular passageway.

8. The method of breaking foam comprising introducing it into a rotating centrifugal bowl, the introduction of foam being effected at one end of said bowl; confining the flow of foam through said bowl to an annular passageway extending longitudinally of said bowl adjacent its periphery; discharging from the opposite end of said bowl the gas resulting from the breaking of foam in said annular passageway; and, without permitting the gas to regain access thereto, reducing the rotational velocity of and discharging the liquid resulting from the breaking of foam in said annular passageway, the discharge of the liquid being accomplished out of contact with air.
